TURBINE-BLADE ATTACHMENT.

1,328,640.

Specification of Letters Patent. Patented Jan. 20, 1920.

Application filed February 4, 1919. Serial No. 274,942.

To all whom it may concern:

Be it known that we, CHARLES ALGERNON PARSONS, STANLEY SMITH COOK, and ANDREW PHILP BENNETT, all subjects of the 5 King of Great Britain, residing at Heaton Works, Newcastle-upon-Tyne, in the county of Northumberland, England, have invented certain new and useful Improved Turbine-Blade Attachments, of which the following 10 is a specification.

The present invention relates to means for securing the last blade of a row of turbine blades which are undercut to fit circumferential projections on the sides of the recesses, and is particularly applicable to constructions in which a blade is 15 integral with or attached to a packing or spacing section.

It is usual in such constructions to provide a local recess in the side of the groove in the blade carrier to allow the blades and spacing sections to be inserted, this recess being subsequently filled by a closing piece or pieces, so as to retain the blades and sections opposite the recess. It is difficult to obtain positive attachment to the blade carrier of the closing piece, or of the last inserted closing piece, as it must be inserted 20 radially and secured by screws, or by calking or similar means. It is therefore desirable when the blade carrier is the rotor that the last inserted closing piece shall not be subject to, or shall only be subject to a small proportion of, the radial forces tending to 25 extract the blades and sections, as thereby the advantages of the positive attachment of the latter to the groove would be lost, so far as the blades, &c., opposite the recess are concerned.

In order to obviate this disadvantage, it has been proposed to make the cross-section of the recess (in a plane parallel to the groove sides) such that the sides are undercut, and to provide a locking piece of the same cross-section but of less width than 45 the recess, so that the locking piece can slide toward and away from the groove. The locking piece is slid away from the groove until the blades and sections are all inserted, after which it is slid into contact with the latter, being so shaped that it registers with the circumferential projections, serrations, &c., in the blades and spacing sections. The recess is then filled with 50 a filling or closing piece, and a positive

hold of the blades to the rotor is thus obtained.

With such constructions, however, the width of the recess (measured perpendicular to the sides of the groove) is great, thus 60 tending to weaken the rotor, and there is great difficulty in machining the undercut sides of the recess, due principally to its having only one open end.

The object of the present invention is to 65 provide a construction in which the blades and spacing sections in a groove are all positively retained against their radial extracting forces without the above mentioned 70 disadvantages.

The invention consists in making the locking piece and the recess in which it is inserted of such circumferential length that it overlaps three or more separate blades and packing sections, and inserting it after 75 the last inserted section and holding it in such a manner that it holds the last inserted section positively in the radial direction while itself is held positively in the radial direction by the adjacent sections, these being held positively in the radial direction 80 by the circumferential groove in which the blades are inserted.

The invention further consists in making the circumferential length of the recess substantially a multiple of the circumferential pitch of the packing sections, in arranging the latter so that each end of the recess occurs substantially opposite the center of the circumferential length of the opposing face 90 of a packing section, and in providing a locking piece of substantially the same length as, but of less thickness than, the recess, one side of this locking piece registering with the serrations or projections of the 95 packing sections, the other side forming contact with a closing piece or pieces which preferably are calked in to fill up the recess and prevent the locking piece from coming out of register with the packing sections.

The invention further consists in the improved means for attaching turbine blades hereinafter described.

Referring to the accompanying drawings:

Figure 1 is a plan view, and

Fig. 1^a is a detail perspective view of a part of the blade carrier showing the groove, the recess and locking means.

Fig. 2 is a sectional elevation of a portion 11

of a turbine rotor, showing one application of the invention.

Figs. 3, 4, 5, 6 and 7 are sectional views showing modifications.

5 Fig. 8 is a plan view of a modified construction.

In carrying the invention into effect according to the example shown in Figs. 1 and 2, in which the blade carrier is the rotor, the 10 steel locking piece A, which in fact completes the side of the groove H, is of a circumferential length equal to two blade pitches, the blades preferably made integral with the spacing sections or packing pieces, 15 being inserted so that the middle of each spacing section or packing piece of blades E, F, is opposite the adjacent end of the piece A. The recess C, which accommodates the locking piece A, is of substantially the same length as, but wider than, the piece A, the face opposite the groove H being undercut. The locking piece A is held in contact with the blades E, G, F by two filling pieces B, D, of brass, copper, or other suitable material, which are calked in position, 20 the face of the locking piece on which they bear being serrated as shown, or smooth.

The face of the locking piece A which engages the blades and their packing piece, 30 has or may have the same configuration as the wall of the groove in which the blades and their packing pieces are located. When it is in position, therefore, it forms a continuation of the groove, presenting the same 35 characteristics as the wall. As this locking piece is longer than the width of a packing piece, its ends overlap and lie opposite the adjacent packing pieces, preferably terminating at about the centers of these pieces. 40 These adjacent pieces are, however, engaged by and interlock with the wall of the groove for a part of their length. They, therefore, are positively held by the wall of the groove and they also positively hold the locking 45 piece. The locking piece in turn positively holds the packing piece of the blade which is between the overlapped packing pieces.

Referring specifically to Fig. 1, the locking piece is longer than the packing piece 50 G, and, therefore, overlaps on the packing pieces E and F. The packing pieces E and F, however, engage the integral ribs on the walls of the groove, so that they are positively held by this engagement. As the locking piece positively engages these positively held pieces, it in turn is held against radial displacement by them, and since it engages the intermediate packing piece G, it holds the intermediate packing piece from displacement.

As shown in Fig. 3, the locking piece A may be formed with a number of projections J for use in connection with blading in which this form of retaining device is used.

In the modification illustrated in Fig. 4,

the recess C, instead of being undercut, is serrated on the face opposite the groove H. Three filling pieces B, D, K also are used, the bottom one being of steel so as to offer a large resistance to compression consequent 70 on transverse bending forces on the blades.

As shown in Fig. 5 the projections on the side of the groove and on the locking piece are perpendicular to the plane of the groove, so that radial blade-extracting forces will 75 not have components in the longitudinal direction, tending to compress the calking or closing pieces.

It will be seen with this construction that so far as radial extracting forces are concerned, each of the blades or sections is positively attached to the rotor. The sections in the groove opposite the ends of the recess and locking piece are positively held by the projections on the sides of the groove 80 formed on the body of the rotor. The locking piece is held by these two sections in the radial direction, also positively, while the last inserted section opposite the center of locking piece is positively held by the projection on the locking piece, this locking piece, as above stated, being also positively held. The whole of the sections are held positively by the projections of the groove on the side opposite the recess. It will be 85 seen, therefore, that the calking or closing pieces are not subjected to the blade extraction forces, their only function being to hold the locking piece in register with the sections opposite to it. 90

It will further be seen that the locking piece is, through its registration with the packing sections, subjected to forces in opposite directions, the sections at the ends of the recess tending to retain it against the 105 outward radial forces of the section or sections wholly within the recess. 100

In the modifications shown in Figs. 6 and 7 the face of the recess C opposite the groove is undercut and preferably serrated, and the 110 face of the locking piece A, which forms contact with the closing pieces is similarly inclined to the plane of the groove. With this construction it will be seen that the tightly calked closing pieces B, D and K, 115 will assist to some extent in resisting the radial extracting forces on the locking piece and the blades and sections with which it is in register. This construction may be employed where it is desired, to have a short 120 recess, as shown in Fig. 8.

In cases where the shape of the sections is such that the last one cannot be inserted from the side, but must be inserted radially, recesses, &c., may be provided at each side 125 of the groove. Each of these two recesses would be provided with a locking piece and closing pieces as described above. As an alternative employing one recess only, part of the last section may be removed to allow it to 130

be inserted from the side, and a filling-up piece used to fill the groove before the locking piece is introduced. This virtually results in making the last inserted section in 5 two pieces, but the filling-up piece may if desired be made integral with the locking piece.

It will be seen that the invention has special advantages in cases where the blades 10 and spacing sections are integral, or are permanently attached to each other before assembling in the rotor groove, as it does not prevent such combination of the last inserted blade and section and at the same 15 time provides a positive attachment to the rotor of all the blades and sections.

Having now particularly described and ascertained the nature of our said invention and in what manner the same is to be performed, we declare that what we claim is:—

1. In a turbine a blade carrier having a groove, blades and packing pieces located in the groove, a recess in a wall of the groove which is circumferentially longer than a packing piece or pieces and so related to the blades and packing pieces that when they are inserted in the groove the recess spans a packing piece or pieces and its ends lie opposite other packing pieces, a locking piece located in the recess and spanning a packing piece or pieces, the ends of said locking piece overlapping the other packing pieces, interengaging projections on the walls of the groove, the packing pieces 35 and locking piece, whereby the overlapped packing pieces positively lock the locking piece, and the locking piece positively locks the spanned packing piece or pieces, and the means for holding the locking piece in the 40 recess.

2. In a turbine a blade carrier having a groove, blades and packing pieces located in the groove, a recess in a wall of the groove which is circumferentially longer than a packing piece or pieces and so related to the blades and packing pieces that when they are inserted in the groove it spans a packing piece or pieces and its ends lie opposite other packing pieces, a locking piece located 45 in the recess and spanning a packing piece or pieces, the ends of said locking piece overlapping the other packing pieces, interengaging projections on the walls of the groove, the packing pieces and the locking piece, whereby the overlapped packing pieces positively lock the locking piece, and the locking piece positively locks the spanned packing piece or pieces, and calking for holding the locking piece in the recess.

3. In a turbine a blade carrier having a groove, blades and packing pieces located in the groove, a recess in a wall of the groove which is circumferentially longer than a packing piece or pieces and so related to the blades and packing pieces that

when they are inserted in the groove the recess spans a packing piece or pieces and its ends lie opposite other packing pieces, a locking piece located in the recess and spanning a packing piece or pieces, the ends of 70 said locking piece overlapping the other packing pieces, interengaging projections on the walls of the groove, the packing pieces and the locking piece, whereby the overlapping packing pieces positively lock the 75 locking piece, and the locking piece positively locks the spanned packing piece or pieces, and calking blocks for holding the locking piece in the recess, the inner one of said blocks being of steel.

4. In a turbine a blade carrier having a groove, blades and packing pieces located in the groove, a recess in a wall of the groove which is circumferentially longer than a packing piece or pieces and so related to the 85 blades and packing pieces that when they are inserted in the groove the recess spans a packing piece or pieces and its ends lie opposite other packing pieces, the face of the recess opposite the packing pieces being 90 undercut, a locking piece located in the recess and spanning a packing piece or pieces, the ends of said locking piece overlapping the other packing pieces, interengaging projections on the walls of the groove, the packing pieces and the locking piece, whereby the overlapped packing pieces positively lock the locking piece and the locking piece positively locks the spanned packing piece or 95 pieces, and calking for holding the locking piece in the recess.

5. In a turbine a blade carrier having a groove, blades and packing pieces located in the groove, a recess in a wall of the groove which is circumferentially longer than a 10 packing piece or pieces and so related to the blades and packing pieces that when they are inserted in the groove the recess spans a packing piece or pieces and its ends lie opposite other packing pieces, a locking piece located in the recess and spanning a packing piece or pieces, the ends of said locking piece overlapping the other packing pieces, interengaging projections on the walls of the groove, the packing 11 pieces and the locking piece, said projections having two surfaces which are oppositely inclined to the plane of the groove side, and means for holding the locking piece in the recess.

6. In a turbine, a blade carrier having a groove, blades and packing pieces located in the groove, a recess in a wall of the groove which is circumferentially longer than a packing piece or pieces and so related to the blades and packing pieces that when they are inserted in the groove the recess spans a packing piece or pieces and its ends lie opposite other packing pieces, a locking piece located in the recess and spanning a pack-

ing piece or pieces, the ends of said locking piece overlapping the other packing pieces, interengaging projections on the wall of the groove, the packing pieces and the locking piece, said projections having two surfaces which are oppositely inclined to the plane of the groove side, and calking blocks for holding the locking piece in the recess.

7. In a turbine a blade carrier having a groove, blades and packing pieces located in the groove, a recess in a wall of the groove which is circumferentially longer than a packing piece, said recess terminating substantially opposite the center of the adjacent packing pieces, a locking piece located in the recess, said locking piece spanning a packing piece and having its ends terminating substantially opposite the centers of the packing pieces adjacent to the spanned packing piece, interengaging projections on the walls of the groove, the packing pieces and the locking piece, whereby the overlapped packing pieces positively lock the locking piece and the locking piece positively locks the spanned packing piece, and means for holding the locking piece in the recess.

8. In a turbine a blade carrier having a groove, blades and packing pieces located in the groove, a recess in a wall of the groove which is circumferentially longer than a packing piece, said recess terminating substantially opposite the center of the adjacent packing pieces, a locking piece located in the recess, said locking piece spanning a packing piece and having its ends terminating substantially opposite the centers of the packing pieces adjacent to the

spanned packing piece, interengaging projections on the walls of the groove, the 40 packing pieces and the locking piece, whereby the overlapped packing pieces positively lock the locking piece and the locking piece positively locks the spanned packing piece, and calking blocks for holding the locking piece in the recess. 45

9. In a turbine a blade carrier having a groove, blades and packing pieces located in the groove, a recess in the wall of the groove which is circumferentially longer than a packing piece or pieces and is so related to the blades and packing pieces that when they are inserted in the groove the recess spans a packing piece or pieces and its ends lie opposite other packing pieces, a 50 locking piece located in the recess and spanning the packing piece or pieces, the ends of said locking piece overlapping the other packing pieces, interengaging projections on the walls of the grooves, the 60 packing pieces and locking piece, and means between the locking piece and the face of the recess opposite the packing pieces for pressing the locking piece into engagement with the packing pieces, the recess being of such a length circumferentially as to permit the radial entrance of the locking piece into the recess at a point close up to the packing pieces, substantially 65 as described. 70

In testimony whereof we have signed our names to this specification.

CHARLES ALGERNON PARSONS.
STANLEY SMITH COOK.
ANDREW PHILP BENNETT.
